Primary Examiner — Melanie Pellegrini

(57) CLAIM

The ornamental design for a mask for disguise, as shown and described.

DESCRIPTION

1. Mask for disguise
- 1.1 : Perspective
- 1.2 : Front
- 1.3 : Left
- 1.4 : Right
- 1.5 : Top
- 1.6 : Bottom
- 1.7 : Reference
